US0D1054632S

(12) **United States Design Patent** (10) Patent No.: **US D1,054,632 S**
(45) Date of Patent: ** Dec. 17, 2024

(54) **HELMET FOR MOTORCYCLISTS**

(71) Applicant: **SHARK**, Marseilles (FR)

(72) Inventor: **Frédéric Doppelstein**, Auriol (FR)

(**) Term: **15 Years**

(21) Appl. No.: **35/518,153**

(22) Filed: **Aug. 3, 2023**

(80) **Hague Agreement Data**

Int. Filing Date: **Aug. 3, 2023**

Int. Reg. No.: **DM/230813**

Int. Reg. Date: **Aug. 3, 2023**

Int. Reg. Pub. Date: **Aug. 25, 2023**
